Application September 6, 1946, Serial No. 695,090

3 Claims. (Cl. 154—126.5)

1

This invention relates to the art of protective bags, wrappers and the like, and more particularly to improvements in the method and apparatus by which the layers, sheets or webs constituting such bags or wrappers are sealed together.

It is an object of our invention to provide improved means for forming and sealing the closures of bags and wrappers by the use of heat. It is a further object to provide improved means and methods for the heat sealing of bags and wrappers which are already partially formed, and which are filled with the intended contents. Still a further object is to greatly simplify the apparatus and process required in such sealing operations, with concomitant savings in the cost of the machines and reductions in the amount of maintenance thereof.

Another object of our invention is to reduce the time required to seal a bag or wrapper, whereby the speed of operation of filling and closing machines may be greatly increased, and the cost of the operations thereby reduced in comparison with prior art systems.

A still further object is to provide a method and apparatus for the use of high-frequency electric energy as the source of the heat used in such sealing operations, whereby the degree of control of temperatures that may be exercised is increased. Our invention makes it possible to perform sealing operations of the type indicated with simpler equipment, at higher speeds and with greater reliability than when gas, electric resistance or other known types of heaters are used, and these improvements are, by the application of the principles disclosed herein, achieved at an actual reduction in the cost of sealing such materials, notwithstanding the relatively higher cost of high frequency power as compared with the sources of heat heretofore used in this art.

An additional object of our invention is to provide a process and apparatus for the heat sealing of bags or similar wrappers made of material which is not inherently heat sealable, but which is coated or printed with an electrically polar heat sealable material on those portions of the surfaces which it is desired ultimately to seal together by application of heat. In connection with this object of our invention, it will be understood that the material itself from which the wrappers are made, generally constitutes a thermal barrier when sealing is done by transfer of heat through such material to reach the heat sealable substance, which greatly slows down the heat sealing process, and hence the rate at which

2

bags or other wrappers can be handled by given machinery.

A still further object of our invention is to provide a method and apparatus enabling the heat sealing of the mouths of filled multi-ply bags, at a rate never before approached by conventional methods attempting to utilize heat conducted through the plies to the sealing compound. As will appear, the existence of several plies of insulating material, such as paper, between the sealing jaws and the sealing compound, has no effect whatever upon the speed with which our process permits such sealing compound to be raised to its sealing temperature.

15 The above and other objects and advantages of our invention will best be understood by reference to the following detailed description of certain preferred embodiments of the invention, taken in connection with the attached drawings, in which:

20 Fig. 1 is a schematic perspective view of a portion of a machine in accordance with the invention, as used for the heat sealing of filled bags.

Fig. 2 is a diagrammatic view of the electrical connections used with the machine of Fig. 1.

25 Fig. 3 is a partial view similar to Fig. 2 but illustrating the parts at a later phase of the operation cycle,

Fig. 4 is a view similar to Fig. 3 but taken at a still later phase,

30 Figs. 5 and 6 are schematic views of the operation of the structure of Fig. 1 at two different points in the cycle,

Fig. 7 is a perspective view of a somewhat modified form of the invention, and

35 Fig. 8 is a sectional view illustrating the relation between a pair of modified electrodes and a gussetted multi-wall sack such as a shipping sack.

Conventional bag and wrapper heat sealing machines, and machines for sealing the mouths 40 of liner bags used inside pasteboard cartons, with

which we are familiar, are alike in that the heat requirements of the adhesive material are supplied by thermal conduction through the material, such as paper, glassine or the like, composing the bag, wrapper or liner which is to be sealed. Usually, such heat is obtained from one or more heated jaws (or members equivalent in function), which are arranged to squeeze together the plies of material to be sealed. After a suitable interval

50 to allow the sealing material to melt or become tacky, said jaws are retracted, the conveyor carrying the bag or wrapper is advanced to a new position, and the joint between the plies is squeezed between a pair of members which are 55 at a relatively low temperature, in order to cool

off the sealed plies and thereby the sealing material. These members are in turn retracted, and the conveyor then operates to move the bag, wrapper or carton to further positions for the performance of other operations.

The prior art system of which the foregoing description is exemplary hence requires the expenditure of a great deal more heat than the simple requirements of melting the heat sealable material, because it is necessary to heat up not only such material, but the paper or other support which carries it, as well as the relatively massive jaws or similar members which conduct the heat to such support. All of these parts are continuously losing heat by radiation, convection and the like to the atmosphere as well as to other machine parts. Further, the requirement of such systems that the heat pass through the support of paper or the like imposes undesirable limitations on the operating speeds obtainable, since not all support materials are capable of withstanding high temperatures for the period required to melt the adhesive quickly, and the incidental heating of such support material may be very deleterious thereto. Also, when the material in the filled package is sensitive to heat, it is often very difficult to force sufficient heat into the areas to be sealed without simultaneously raising the temperature of the contents of the bag or wrapper to an undesirable level.

We have discovered that it is possible to perform the heat sealing of bags, wrappers and the like without any of the disadvantages above mentioned, by the application of high frequency heating, especially dielectric heating; our invention makes it possible to supply the desired quantity of heat directly to the heat sealing material without having to pass such heat through any other elements. To accomplish this, we establish a high frequency electric field between electrodes lying preferably on either side of the mouth of the bag to be sealed, the frequency of the field being chosen so as to achieve a maximum practical amount of dielectric loss in the particular heat sealing material being used. In this way, we are enabled to heat the adhesive with a minimum of concomitant heating of the paper or the like on which it is coated, and with substantially 100% utilization of such heat as is developed.

The above discussion is applicable as well to materials which are inherently heat sealable (e. g., vinylite, pliofilm) by what may be termed autogeneous welding, as to materials which are not themselves heat sealable but which are provided with heat sealable areas by the application to such areas of a layer of material of desired characteristics; examples of such coated wrapper materials, and of the appropriate coatings therefor, are given in the patent to Bell, No. 2,237,327, dated April 8, 1941. In the latter cases, however, our process is more advantageous than in the former, for the reason that it is possible to select a frequency which preferentially heats the coated heat sealable substance as compared with its paper carrier, so that the efficiency of application can be greater, and higher production speeds obtained, than in a case where the high frequency field heats the material of the wrap indiscriminately throughout its thickness, much of such heat (that is, the heat not generated closely adjacent the surfaces to be sealed) being wasted insofar as the heat sealing is concerned. Such waste heat is in fact a positive detriment, as it operates to reduce the cooling

or settling time of the portions which have been sealed together.

In the case of multiwall bags, for example shipping sacks, the presence of several insulating layers of paper or like materials between the outside of the sack and the areas which must be sealed has effectively prevented the application of heat sealing techniques to such containers. In accordance with our process, these intermediate layers may be by-passed insofar as heating an internal layer of sealable material is concerned, by so choosing the frequency of the oscillation as to make the power loss, and hence heat generated, in the sealing material, much greater than the loss in the intermediate paper layers. Concurrently, the presence of the unheated outer layers of paper enables faster cooling of the sealed material after the heating phase of the process has been concluded.

We have found that multi-wall shipping sacks may be satisfactorily sealed in the above way at a higher rate, and with less bulky and complex equipment, than by any known commercially practicable method. In fact, we believe that we are the first to present a process of commercially practicable speed for the heat sealing of multi-wall sacks of heavy caliper paper, notwithstanding the fact that heat sealing of such bags has long been attempted without success by other means.

In the application of the above principles to the high speed heat sealing of protective bags, we have found that it is particularly desirable to utilize the metallic electrode members also as the pressing jaws of the sealing station. This application is very advantageous, since such electrodes may be maintained at any desired low temperature without adversely effecting their efficacy as high frequency electrodes, and hence the application of such jaws directly to the bag material after the heating phase of the cycle simultaneously "freezes" the sealing material and holds the bag layers together. Hence, it is feasible to perform all the sealing steps of heating the adhesive, pressing the layers together, and cooling the joint, at a single station, as compared with the two or more stations of the prior art. Great savings in machine complexity and in machine time per sealed bag are thus obtained.

Referring now to Fig. 1 of the drawings, we have shown the sealing station of a machine adapted to seal filled protective bags such as the bag 10, which is provided with an internal band 12 of heat sealable material adjacent its open mouth 14, and is inserted in a carton 15 which will ultimately be closed about the sealed bag. It will be understood that bag 10 has already been filled, by hand or by apparatus not shown. A conveyor 16 is provided to move the bag 10 into sealing position and away from such position, means being provided to start and stop such conveyor in timed relation to the other parts to be described. Such means are well known in the art, and hence we have omitted a description thereof since these form no part of our present invention.

A pair of metallic electrodes 18, 20 are so mounted with respect to the path of bags on conveyor 16 as to be reciprocable toward and away from a bag on such conveyor, as indicated by arrows in Fig. 1. Each electrode is connected, as shown in Fig. 2, by conductors 22, 24 to a source of high frequency power such as the oscillator 26, which is powered from the supply

mains by conductors 28. In order to limit the application of the high frequency power to the electrodes to those periods in which it is required, we have indicated a control means such as a mercury switch 39 of known type, mounted for rotation by a shaft 34 having a vane 36 at its end. A switch control member 38 is mounted on one electrode 20, and comprises two arms 46 and 42, lower arm 40 being straight and upper arm 42 being somewhat longer and provided with a latch-like element 44 pivoted thereto as at 46 and hanging down so as to contact the upper extremity of vane 36 of switch 39. The parts are so adjusted that as, or shortly after, electrode 20 begins to move toward bag 10 (see Fig. 3), latch element 44 strikes the upper end of vane 36, rotating switch 39 to initiate the flow of power to the electrodes. Switch 39 remains in its rotated position as electrode 20 continues to move inward, until, just before the electrodes touch the bag material, lower arm 40 strikes the lower end of vane 36 (Fig. 4) and rotates switch 39 to the "power off" position. The remainder of the motion of electrodes 18, 20 operates to squeeze the joint between the layers of bag 10, and since such electrodes are cool, the sealing material is simultaneously frozen to complete the seal. It will be understood that electrodes 18 and 20 are normally approximately at room temperature, since no heat is applied thereto, but if conditions require, they may be finned or cooled by other means to any temperature desired, e. g., by the use of a circulating refrigerant.

Upon the retraction of electrodes 18 and 20, switch 39 does not operate to turn the power on again, since latch element 44 slips up over the end of vane 36 in its retrograde movement, and electrode 20 continues its reverse movement to its rearward position in preparation for the next cycle.

It will have been observed from the above description that power is drawn from oscillator 26 during only a small portion of the complete cycle of electrode motion. In actual operation this portion may be as small as one-tenth of the total cycle in some applications, which enables the use of an oscillator whose continuous power delivery rating is much smaller than would be required if the heating power were drawn continuously. All that is necessary is to design the oscillator, according to well known principles, so that it can handle short surges of power up to ten or more times its continuous power rating, so long as the long-time average of power drawn is within such rating. By this means, a smaller and less costly oscillator may be employed than would be the case if the oscillator design were such that its instantaneous power rating were no higher than its continuous rating.

When sealing bags of the type illustrated in Fig. 1, it may be desirable to stretch the mouth of the bag just prior to the application of the sealing pressure, in order to insure smooth contact between the two layers of bag material, and to prevent wrinkles therein. We have illustrated in schematic fashion elements which perform such a function, comprising a vertically reciprocable element 46 which carries two crank arms 48, 50 pivoted thereon as at 52, 54, and biased toward each other by a spring 56. Stop pins 58, 60 are mounted on element 46 to maintain the crank arms normally in the position shown in Fig. 1. A pair of pins 62, 64 are secured on a fixed part 66 of the machine, and are

so located that, when element 46 moves downwardly, crank arms 48, 50 are rotated by reason of their contacting the pins 62 and 64, and hence the power end of each is swung outwardly. 5 Pivotedly secured to the lower end of each crank is a two armed lever (68, 70 respectively), connected through one of its arms and a spring (72, 74 respectively) to the crank arm. Stop pins 76 on the lower end of each crank arm 48 and 50 serve to maintain the levers 68 and 70 normally in the position shown.

As element 46 moves downwardly and crank arms 48, 50 swing outwardly, the lower ends of levers 68 and 70 engage within the bag mouth and draw it out until the front and rear surfaces of the bag material lie close together. Just as, or slightly before, jaws or electrodes 18 and 20 reach a point at which they contact the bag material, the lower ends of levers 68 and 70 slip 15 out of contact with the bag, and springs 72 and 74 snap the levers into alignment with crank arms 48 and 50, which are now in such a position that neither they nor levers 68, 70 interfere with the pressing of the bag mouth between the electrodes. As electrodes 18 and 20 are retracted, 20 element 46 moves upward, the bag moving forward on its conveyor, and the parts ultimately resume their Figure 1 position.

Figs. 5 and 6 diagrammatically show the relative positions of the element 46, crank arms 48 and 50, and levers 68 and 70, prior to engagement of the electrodes with the bag, and immediately after the levers have slipped out of the bag mouth.

35 In the form of the invention shown in perspective in Fig. 7 of the drawings, a conveyor 100 is provided, which carries cartons such as 102 each containing a filled bag 104 with a heat sealable band 106 around its inner mouth surfaces. The conveyor 100 in this embodiment moves continuously rather than step-by-step, and conveys the bag mouths between a pair of electrode rails 108 connected to a high-frequency source 110 by any convenient means. The rails 108 are substantially spaced apart at the entrance end, but converge until they are only a fraction of an inch apart at the bag position indicated in the figure. In other words, the electrode rails themselves operate to force the walls of the bag mouth towards one another, the gussets being collapsed rather than extended as in the previously described embodiment. High frequency heating occurs all along the path of the bag between the rails 108, and as the bag mouth 50 passes out of the field between these rails, it is received between a pair of belts 112, 114 mounted to travel in a horizontal plane by means of rollers 116. The arrangement of the belts is such as to form a pinching entrance portion 118 which narrows until the belts are substantially in contact, and at which point they serve to compress the bag mouth to complete the seal, the sealing material cooling as the sides of the bag mouth are held in contact during passage between such belts.

60 It will be understood that belts 112, 114 are at room temperature, or maintained at an even lower temperature by cooling means, whereby the adhesive material is rapidly set and the bag emerges from between the belts with the mouth completely sealed.

We have found that it is necessary to maintain the voltage supplied by the oscillators at a rather low value in order to prevent voltage breakdown of the material of which the bags or wrappers 75 are made, since the separation of the electrodes

in either of the above embodiments becomes very small indeed at some points in either process. We have found that, while it is therefore difficult to obtain a sufficient power dissipation in the heat sealable materials to heat them to the softening or sealing temperatures, a desirable speed of sealing can be obtained even at the necessarily low voltage, by raising the oscillator frequency to a point above that at which dielectric heating is usually carried on.

A frequency in excess of 150 megacycles per second is very desirable, and permits the small volume of heat sealable material per bag to be heated as required by an instantaneous high frequency power of the order of 500 watts, corresponding to a heating period of one-tenth the total operating cycle, and an average oscillator rating of only 50 watts. No difficulty is experienced in obtaining this quantity of power at the frequencies indicated, by use of suitable present day high frequency tubes and circuit designs. The above data are based upon the sealing of bags having a sealing area of approximately eleven square inches, at the rate of sixty bags per minute.

The above descriptions relate principally to the sealing bags or similar wrappers consisting principally of a single layer of wrapper material coated interiorly with a layer or localized area of dielectrically lossy thermoplastic adhesive. Since, as already pointed out, a proper selection of oscillator frequently permits such an adhesive to be heated to its melting point with a minimum of waste of heat in the support layers themselves, it is clear that a wrapper or bag consisting of a plurality of plies of paper or the like may be sealed in a similar manner. The advantages to be gained by the use of our invention in sealing such materials are even greater than in the case of single-ply materials, since attempts to heat an internal adhesive to its melting point by conduction through a plurality of paper plies require so much time as to make such a process commercially impractical. In accordance with our invention, the energy required for this application is little if any greater than in the case of a single-ply material, since at the proper oscillator frequency only a trivial amount of the energy is converted into heat within the paper layers themselves.

The above considerations apply as well where the multi-ply bag has only a single internal layer or localized area of heat sealable material, and where a layer or stripe of such adhesive is located also between the plies of the bag material. The latter situation arises where it is desired, in one operation, not only to seal the mouth of the bag but to seal together the plies of the bag material adjacent the mouth, for greater strength or improved appearance.

The utilization of the improved methods above described enable a maximum amount of heat to be generated at the point of actual use, rather than by conduction through the support materials. The speed with which bag or wrapper sealing operations may be carried on, however, depends also to some extent upon the rate at which heat can be removed from the sealing material once it has been melted, and the joinder of the support layers, such as paper, accomplished. This is because it is necessary that the thermoplastic material be substantially solidified before pressure upon the seal can be released. Such a limitation on operation speed is not, of course, as serious as the limitation arising from the

necessity of melting the material initially, because in the latter case the material must ordinarily be raised from approximately room temperature to its melting point, whereas in the cooling phase 5 of the process it is only required that the material be cooled from its melting point to a temperature slightly below that point—in other words, the heat required to be extracted prior to release of pressure is only a fraction of that required to be applied to melt the adhesive originally. Nevertheless, it is often desirable to accelerate the cooling process, particularly where it has become, due to the use of our novel heating arrangement, the limiting factor on machine 10 speed. This can be accomplished very satisfactorily by simply providing the electrodes or sealing jaws with means for circulating a coolant or refrigerant there through, or even by providing heat exchange fins upon such electrodes to 15 utilize to a maximum the cooling effect of the ambient atmosphere.

In multi-ply work, as suggested above, it is very likely that the process speed will be limited by the cooling time of the adhesive, rather than by its 20 heating time, since the latter is not restricted by the necessity of utilizing heat conducted through the multiple layers of wrap material. Under these circumstances, we prefer to use an adhesive which has a higher melting point than 25 that ordinarily used for single-ply materials. This may slightly increase the time required for the heating phase of the cycle, but such an increase will be more than offset by the reduction in cooling time to the set point of the adhesive, 30 yielding an over-all saving in the process time required. This is because of the fact that the temperature gradient between the adhesive and its surroundings, at the commencement of the 35 cooling phase, will be greater for high melting-point adhesives, whereby the time required for the adhesive to drop to its setting temperature is reduced.

In using the techniques of the present invention in connection with the sealing of large multi-ply sacks or bags intended for rough usage, 40 such as shipping sacks for the transportation of coffee, cement, chemicals or other commodities in quantities of the order of 100 pounds or more, it is clear that the saving in time as against sealing by conductive means becomes much greater 45 than in the case of a relatively few plies of relatively thin materials. A typical shipping sack may be formed of four, six or more plies of kraft paper of sixty pounds basis weight, and hence 50 the thickness of the bag mouth, particularly at the gusseted edges, may approach a quarter of an inch. Since in a bag formed of six-ply paper there are 24 plies adjacent the gussets but only twelve plies at the central portion, there will 55 be a considerable difference in thickness, as indicated in Fig. 8. As shown in that figure, such a condition may be compensated for by shaping the faces of electrodes 218, 220 so as to flare outwardly at their ends, providing a greater spacing 60 between electrodes at points adjacent the gussets. This construction enables uniform pressure to be applied throughout the face of the closure notwithstanding the variations in thickness which result from the gussets.

The electrodes illustrated in Figure 8 also show the provision of internal channels 222 adapted to the circulation of a suitable coolant, which maintains such electrodes at a desired low temperature. By this means, cooling of the outer 75 plies of the shipping sack commences immedi-

ately upon contact with the electrodes, and indeed cooling of the outer plies may go on simultaneously with the generation of sealing heat between the two innermost surfaces of the closure. This type of operation enables a perfect seal to be obtained in a minimum of operating time.

It will be understood that heavy duty multi-wall sacks or bags such as those referred to above will be provided with a suitable mechanical type of closure securing means, such as a sewed closure, for mechanical strength, the heat seal at the bag mouth being provided principally to insure a moisture-proof and sift-proof seal. If the sewed closure is completed prior to the forming of the heat seal, the heat sealing material will effectively seal around the sewn threads and block this possible avenue of leakage at the closure. However, it is quite possible to complete the heat seal before the filled bag is mechanically secured.

We are aware that many changes and modifications may be made in the arrangements and processes described herein, and we therefore do not wish to be restricted to the precise exemplary details recited. In particular, we are aware that the principles of local conversion of electrical energy to heat may be extended to the use of high frequency magnetic fields, as opposed to dielectric fields, and that such an extension has particular applicability to the sealing together of materials whose meeting surfaces comprise layers of metallic foil bearing a heat sealable material thereon, e. g., in the case of a foil-lined bag or wrapper provided with an internal area of thermoplastic adhesive. In such a case, the presence of the electrically conductive metal layer effectively prevents the use of an electric field for sealing, as such layer completely shields the thermoplastic material. However, the use of a magnetic field enables heat to be generated within the metal layer itself due to well known eddy-current effects, and such localized heat readily effects the melting of the adhesive coated thereon. As in the previous application, the melting of the adhesive is in no wise impeded by the presence of numerous outer layers of paper or other thermally insulating materials comprising the wrapper, since here, again, the heat required is generated substantially at the point of use rather than requiring to be conducted through the outer layers of the bag or wrap material.

We also wish it to be understood that our invention is applicable to other operations than the sealing of filled bags or wrappers, in that its principles may very well be applied in an obvious manner to the sealing together of any layers of heat sealable material having the proper dielectric characteristics. For example, the invention may be utilized in the bottoming of formed tubes to form the normally closed end of an empty bag, such as by forming a tube of a suitable heat sealable material, cutting off a length of such tube, flattening said length, and either effecting a simple fin-type closure of one end, or folding the flattened tube back upon itself and sealing the two walls of the tube together and to an outer surface of said tube in one and the same operation, as in the well known Simplex bag machine.

In using the term "heat sealable material"

herein, we intend to include not only materials which are inherently heat sealable, such as the examples mentioned earlier in this specification, on one or both sides, but also materials such as paper, glassine or the like which are rendered heat sealable by the application of a localized or a distributed coating of a heat sealable material such as those mentioned in the Bell patent referred to above.

10 In view of the many changes and modifications which may be made in the invention without departing from the spirit thereof, we do not wish to be restricted to the precise details disclosed, but desire to include within our invention all such changes and modifications as come within the scope of the appended claims.

We claim:

1. The process of sealing together thin layers of heat-sealable, dielectric materials, comprising supporting said layers in face-to-face relationship between a pair of electrodes, exposing said layers to the action of a high-frequency electrical field of at least 150 megacycles per second between said electrodes for a sufficient time to raise said layers to a sealing temperature, then discontinuing said electrical field and immediately thereafter pressing said layers together to seal the same to one another.

2. The process of sealing together thin layers of heat-sealable material, comprising supporting said layers between a pair of thermally conductive electrodes maintained below the sealing temperature of said material, and out of contact therewith, establishing a high-frequency dielectric field between said electrodes for a sufficient time to raise said layers to a sealing temperature, then discontinuing said electrical field and immediately thereafter pressing said layers into intimate contact between said electrodes to seal the layers to one another.

3. A method for sealing together layers of heat sealable materials, comprising placing said layers in facing relationship, subjecting said layers to a high frequency field of at least 150 megacycles per second for a length of time sufficient to soften said heat sealable material, removing said high frequency field, and forcing said softened layers into intimate contact to thereby bond said layers together.
